[57] **CLAIM**

The ornamental design for a holder for bottle and syringe, as shown and described.

DESCRIPTION

FIG. 1 is a perspective view of a holder for bottle and syringe showing my new design;

FIG. 2 is a front elevational view thereof;

FIG. 3 is a side elevational view thereof, the opposite side being a mirror image;

FIG. 4 is a rear elevational view thereof;

FIG. 5 is a top plan view thereof; and

FIG. 6 is a bottom plan view thereof.

The broken line showing of the bottle and syringe in FIG. 3 is for illustrative purposes only and forms no part of the claimed design.
